United States Patent Office.

HENRY DOEBELE, OF PHILO, OHIO; ASSIGNOR TO HIMSELF AND PETER KRIER, OF THE SAME PLACE.

Letters Patent No. 67,420, dated August 6, 1867.

IMPROVED BED-BOTTOM.

The Schedule referred to in these Letters Patent and making part of the same.

TO ALL WHOM IT MAY CONCERN:

Be it known that I, HENRY DOEBELE, of Philo, in the county of Muskingum, and State of Ohio, have invented a new and improved Spring-Bed Bottom; and I do hereby declare that the following is a full, clear, and exact description thereof, which will enable others skilled in the art to make and use the same, reference being had to the accompanying drawings, forming part of this specification, in which—

Figure 1 represents a longitudinal vertical section of a bedstead that is provided with my improved bed-bottom.

Figure 2 is a vertical cross-section of the same, the plane of section being indicated by the line $x x$, fig. 1.

Figure 3 is a detail plan view of the same, showing the connection between the slats and their supports.

Similar letters of reference indicate like parts.

This invention relates to a bed-bottom which is so constructed that it can be easily taken out of the bedstead to be cleaned, and which can be taken apart for transportation whenever desired, and easily put together again. It can be adapted to single or double beds or lounges, as may be desired.

The invention consists in the use of two long wooden strips, in which the slats are fastened in such a manner that, by means of four screws, the whole bed-bottom can be connected. Rails are arranged on the sides of the bedstead for the side pieces of the bottom to rest upon; and between the said rails and side pieces are interposed springs, which are secured to the rails.

A A represent the slats, made of wood or any other suitable material. Any desired number of them may be used in any one bedstead. B B are longitudinal strips, being notched on their upper ends to receive the ends of the slats, on which tenons are formed, to fit into the notches, as is clearly shown in fig. 3. C C are rails firmly attached to the sides of the bedstead. Springs D D are secured to them by means of screws. To the upper edge of each strip A is fastened another strip, E, of the same length, in such a manner that it projects over the outer side of the strip A, as is clearly shown in fig. 2. The under side of the projecting portion of the strips E serves as the supporting surface of the bed-bottom, as it rests upon the springs D, as shown. The strip E also covers the tenoned ends of the slats A, and keeps the latter in their places upon the bars B. By means of metallic elbow-pieces F F, arranged at the ends of the same, the pieces A and E are connected, the same also protecting the said strips from wear and injury. Screws G G are passed through the strips E into the ends of two or more of the slats, whereby the whole bed-bottom will be connected into one. By removing these screws the slats will be released from the side strips of the bottom, and the same can be taken to pieces for transportation. The bottom can at all times be taken out of the bedstead, in which it is not fastened by any devices.

Having thus described my invention, what I claim as new, and desire to secure by Letters Patent, is—

1. Securing the ends of the slats A A between two plates or strips B and E, and connecting the latter by means of metal elbow-pieces F F, and holding the whole bottom together by means of screws G, substantially as set forth.

2. Combining the above bed-bottom with a bedstead, in which are rails C and springs D for the reception of the bottom, so that the latter can be placed upon the springs and be securely held in the bedstead without being fastened to the same, as set forth.

HENRY DOEBELE.
